SANDAL

Clarence E. Hosker, Watertown, Mass., assignor to
The B. F. Goodrich Company, New York, N. Y.,
a corporation of New York

Application March 29, 1939, Serial No. 264,763

1 Claim. (Cl. 36—11.5)

This invention relates to sandals for personal wear and is especially useful in the construction of beach sandals.

The principal objects of the invention are to provide comfort, pleasing appearance, to provide simplicity of construction, to provide resistance to wear, and to provide resistance to dampness.

These and other objects will appear from the following description and the accompanying drawing.

Of the drawing

Fig. 1 is a perspective view of the sandal constructed according to and embodying the invention.

Fig. 2 is a side view of the sole structure.

Fig. 3 is a cross-sectional view, taken on line 3—3 of Fig. 2.

Referring to the drawing, the numeral 10 designates a clog type sole and heel comprising a body 11 of wood, cork, compressed fibrous material, or other light weight fibrous material, preferably of thick construction, formed on its upper face to the contour of the foot of the wearer, and preferably, though not necessarily, formed with a hollow shank 12 between the heel and sole portions.

To provide for protecting the sole from moisture, a covering 13 of moisture-impervious material, such as vulcanized rubber composition or other rubber-like material completely envelopes the sole. This covering may be formed in situ by depositing a coating about the sole from a solution or dispersion of the coating material, or may be made by assembling sheeted rubber-like material about the sole and seaming the same so as completely to enclose and protect the sole.

To provide a wear resisting surface, a tread layer 14, of wear resisting material, such as crepe rubber, rubber composition, or leather is applied to the tread surface of the sole over the protective layer 13. The tread layer preferably extends as a continuous covering over the tread and breast faces of the heel, the shank, and along the sole to the toe of the sandal, thereby to afford

wear protection to the entire tread surface including the instep.

The upper of the sandal may be of any suitable construction. In the sandal illustrated it comprises a counter 15 and spaced therefrom forwardly of the counter, a vamp 16 in the form of a strap extending from edge to edge of the sole and permitting exposure of the toes. The counter and vamp may be of any desired material, a knitted textile material being preferred. They are secured by adhesion or in any other suitable manner to the sole over the covering 11. An insole 17 is applied over the upper surface of the sole over the lower margins of the upper to protect the wearer's foot from discomfort. If desired, the upper and insole may be coated or impregnated or otherwise moistureproofed.

To provide for attaching the sandal to the foot, eyelets 18, 19, are attached to the vamp and counter, and a lace 20 is inserted therethrough so as to cross over the instep.

Various modifications may be made without departing from the scope of the invention as it is defined by the following claim.

I claim:

An article of footwear comprising a sole body of light weight fibrous material and of substantial thickness, a thin seamless waterproof covering of rubber-like material completely enclosing said body including the top, bottom, and side faces thereof and having the characteristics of material deposited from a dispersion of rubber-like material, a wear-resisting outer sole of rubber-like material adhered to said covering over the tread face, an upper having inwardly turned margins adhered to the covering at the face of the sole opposite the tread face, and an insole adhered to said covering and inwardly-turned margins, the attachment of said upper, insole, and outersole being solely by the adhesion to said seamless covering providing completely waterproof protection to said body of fibrous material under the stresses of use.

CLARENCE E. HOSKER.
